UNITED STATES PATENT OFFICE.

HERBERT S. RAUH, OF NEW YORK, N. Y.

DESIGN FOR A GAITER.

Application filed May 22, 1922. Serial No. 2,367. Term of patent 7 years.

To all whom it may concern:

Be it known that I, HERBERT S. RAUH, a citizen of the United States, and a resident of the city of New York, county of New York, State of New York, have invented a new, original, and ornamental Design for Gaiters, of which the following is a specification.

Reference is to be had to the accompanying drawing, in which Figure 1 is a front elevation of a gaiter embodying the design;

Fig. 2 is a side elevation thereof, and Fig. 3 is a section on the line 3—3 of Fig. 1.

It is to be understood that my claim includes all substantial equivalents of the design as shown and described.

I claim:

The ornamental design for a gaiter as shown and described.

HERBERT S. RAUH.
